R. M. MILLIGAN.
HINGE FOR DESK TOPS.
APPLICATION FILED DEC. 1, 1919.

1,343,332.

Patented June 15, 1920.

UNITED STATES PATENT OFFICE.

ROCKWELL M. MILLIGAN, OF ST. LOUIS, MISSOURI, ASSIGNOR OF ONE-FOURTH TO
GEORGE T. MEYER AND ONE-FOURTH TO FREDERICK W. LINNEMAYER, BOTH
OF ST. LOUIS, MISSOURI.

HINGE FOR DESK-TOPS.

1,343,332.

Specification of Letters Patent. Patented June 15, 1920.

Application filed December 1, 1919. Serial No. 341,700.

To all whom it may concern:

Be it known that I, ROCKWELL M. MILLIGAN, a citizen of the United States of America, a resident of the city of St. Louis, in the State of Missouri, have invented certain new and useful Improvements in Hinges for Desk-Tops, of which the following is a full, clear, and exact description, reference being had to the accompanying drawings, forming a part of this specification.

My invention relates to hinges for connecting pivotal sections of desk tops to stationary desk top sections, such hinges being more particularly intended for use in school desks. One of the objects of the invention is to provide hinges for this purpose which permit of the pivotal desk top section being elevated and supported in an inclined position to serve as an inclined book support with a book resting thereon in the correct line of vision of a person seated back of such book support. A further object of the invention is to provide hinges for the purpose mentioned which do not obstruct the desk top surface to interfere with writing thereon even at the junction of the pivotal and stationary desk top sections, or the movement of papers or books on such surface. A still further object of the invention is to provide for the hinging of the pivotal desk top section in such manner as to obviate material separation of said pivotal section from the stationary desk top section at all times, thereby avoiding the occurrence of crevices between such parts in which human fingers may be caught and injured. A still further object of the invention is to provide a hinge whereby a movable desk top section may be so supported as to approximately eliminate noise in its operation.

Figure I is a rear elevation of a desk top including my improved hinges.

Fig. II is a side elevation of the desk top with one of the hinges shown as it appears when the pivotal desk top section is in lowered position.

Fig. III is a view similar to Fig. II, with the pivotal desk top section in elevated inclined position and one of the hinges shown as it appears in the altered position of said section.

Fig. IV is an enlarged side elevation of one of the hinges.

Fig. V is a vertical section through one of the hinges.

55

Fig. VI is a side view of one of the movable hinge leaves.

Fig. VII is a side view of one of the intermediate hinge leaves.

Fig. VIII is a side view of one of the stationary hinge leaves.

Fig. IX is a vertical section taken on line IX-IX, Fig. I, showing the inner face of one of the hinges in elevation.

In the drawings, A designates a stationary desk top section secured to a support B, and C a pivotal desk top section movable from a position in which its surface is aligned with the surface of the stationary section A to an elevated position in which said pivotal section is inclined forwardly over the stationary section to serve as a sloping book support. Hinges made in accordance with my invention connect said desk top sections in a manner to permit a long arcuate movement of the pivotal section relative to the stationary section with slight separation of their adjoining edges.

Two hinges D, D', constructed in accordance with my invention, are used to join the pivotal desk top section C to the stationary desk top section A, and these hinges being substantially alike, a description of the hinge D as herein given will be applicable to the hinge D', except for a detail feature appended to the hinge D, which will be later set forth.

The hinge D includes, primarily, a main leaf 1 adapted to be rigidly secured to the stationary desk top section A by any suitable means, so that it extends vertically at one end of said section and projects rearwardly beyond the rear edge of the said stationary section. In said hinge-leaf at its upper edge, and adjacent the rear edge of the desk top section A, is a pintle hole 2. Beneath said pintle hole is a segmental lower member 3 of the hinge-leaf 1, the bottom edge 4 of which occupies an arc of a circle drawn from the pintle hole 2. At the forward end of said segmental member 3 is an abutment 5, and at the rear end of the same member is an abutment 6 at which the curved bottom edge of the segmental lower member 3 terminates. Immediately above 100 said last mentioned abutment 6 is a ledge 7,

which overlies the rear end of the segmental member 3.

- 8 designates a second main leaf of the hinge D secured to the movable desk top section C. This hinge-leaf comprises an arm 9, preferably of angle shape in cross section, which extends rearwardly beneath the desk top section C and receives the fastening means for attaching the leaf 8 to said section. 5 At the forward end of the leaf 8 is a segment 10 having curved bottom edges 11, the segment terminating at the front of said curved bottom edge 11 in an abutment 12. Above the segment 10 of the hinge-leaf 8 is 10 a pintle-receiving member 13, containing a pintle hole 14 that receives a pintle 15, also located in the pintle hole 2 in the main hinge-leaf 1, and by which the two main hinge-leaves 1 and 8 are pivoted to each 15 other. 20
- It will be apparent that by connecting the described hinge-leaves 1 and 8 through the medium of the pintle 15, the desk top section C is pivoted to the desk top section A, 25 but it will be perceived that inasmuch as the hinge-leaves 1 and 8 are merely arranged side to side, and no provision made for limiting the movement of the leaf 8 relative to the leaf 1, the said hinge-leaves would not 30 provide for the pivotal desk top section C being sustained in a forwardly inclined position above the stationary desk top section for use as a book support. To provide for the hinge supporting the pivotal desk top 35 section in the desired inclined position, I incorporate therein an auxiliary or intermediate hinge-leaf, a description of which I will now proceed to give.

- The intermediate hinge-leaf, designated 40 by the character 16, is preferably segmental in shape and is provided at its apex or top with a pintle hole 17, through which the pintle 15 extends to suspend said intermediate leaf between the two main hinge-leaves 1 and 8 with its lower curved edge 18 approximately flush with the lower curved edges of the segmental portions of the main hinge-leaves. 45

- At the forward end of the intermediate hinge-leaf 16 is an abutment 18 in the form 50 of a tongue, said abutment extending outwardly across the lower edge of the segmental lower member 3 of the main hinge-leaf 1 in a position to engage the abutment 5 at the forward end of said segmental portion, as seen in Figs. II and IV. At the rear end of the intermediate hinge-leaf is an 55 abutment 19.

end of the main hinge-leaf 1, when the pivotal desk top section is in a lowered position, as seen in Figs. II and IV.

It will be understood from the foregoing that when the pivotal desk top section C is 70 in the lowered position shown in Figs. II and IV, it is supported due to the abutment 18 on the intermediate hinge section 16 resting against the abutment 5 on the main hinge-leaf 1 and the stop 20 resting upon the 75 ledge 7, thereby limiting the movement of the intermediate leaf, and finally due to the main hinge-leaf 8 being seated on the abutment 19 at the rear end of the intermediate hinge-leaf. 80

Between the front and rear ends of the intermediate hinge-leaf 16 is an abutment 21, which extends from the lower edge of said intermediate hinge-leaf across the lower edge of the main hinge-leaf 8, this abutment 85 being preferably in the form of a tongue which projects from the lower edge of the intermediate hinge-leaf, extending beneath the lower edge of the main hinge-leaf 8 and then upwardly alongside of the latter leaf. 90

When the pivotal desk top section C is elevated from its lowered position seen in Figs. II, IV and IX to the inclined position illustrated in Fig. III, the intermediate hinge section 16 is brought into action in the 95 following manner:

During the initial upward movement of the pivotal desk top section, the hinge-leaf 8 first moves independently of the intermediate hinge-leaf 16, this independent movement continuing until the abutment 12 at the forward end of the leaf 8 strikes the abutment 21 between the ends of the intermediate hinge-leaf. The main hinge-leaf 8 then picks up the intermediate hinge-leaf 100 due to the engagement of the abutments 12 and 21, and said parts move together until the abutment 18 at the forward end of the intermediate hinge-leaf is brought into engagement with the abutment 6 at the rear 110 end of the main hinge-leaf 3. The intermediate hinge-leaf is by the engagement of the abutments 18 and 6 held from further movement, and the main hinge-leaf 8 is retained in fixed relation to the intermediate hinge-leaf 115 due to continued contact of the abutment 12 with the abutment 18. The several abutments co-operating with each other in the manner just explained are so related to each other in their positions on the hinge-leaves as to provide for the abutments 18 and 6 engaging each other when the pivotal 120 leaf 8 is retained in its inclined position.

movement in consequence of its abutment 12 being in contact with the abutment 21 on the intermediate hinge section.

As previously stated, the hinges D and D' are similar in structure and the foregoing description is applicable to the hinge D' as well as to the hinge D.

A hinge constructed in accordance with my invention serves to fully support a movable desk top section in such manner as to avoid the striking of the said section against a stationary section or other fixed object adjacent to the hinge, and consequently the possibility of noise in the movement of the movable desk top section is substantially eliminated.

My hinges are particularly intended for use upon school desks in the stationary top members of which it is customary to dispose ink-wells, as seen at X. The ink-well as here indicated is located at the end of the stationary desk top section A adjacent to the hinge D, and to protect the bottom of said ink-well I provide the hinge D with a guard 22, which extends inwardly from the main hinge-leaf 1 to the support B, as seen in Figs. I and II.

I claim:

1. A hinge comprising pivotally connected main leaves and a pivotal auxiliary leaf for engagement with said main leaves to limit the pivotal movement of one of the main leaves relative to the other main leaf.

2. A hinge comprising pivotally connected main leaves and an auxiliary leaf pivoted on a common center, said auxiliary leaf being adapted to limit the pivotal movement of one of said main leaves relative to the other main leaf.

40 3. A hinge comprising pivotally connect-

ed main leaves and an intermediate auxiliary leaf movable relative to the main leaves, said auxiliary leaf being provided with means for engagement by one of the main leaves to be moved thereby, and with means 45 for engagement with the other main leaf to limit the pivotal action of the hinge.

4. A hinge comprising a stationary main leaf, a movable main leaf pivoted to said stationary leaf, and a pivotal auxiliary leaf 50 said movable main leaf being provided with an abutment for engagement with said auxiliary leaf to impart movement thereto, and said stationary main leaf being provided with an abutment adapted to be engaged by said auxiliary leaf to restrict the pivotal action of the auxiliary leaf and the movable main leaf.

5. A hinge comprising a stationary main leaf, a movable main leaf pivoted to said stationary main leaf, a pivotal auxiliary leaf 60 having an abutment intermediate of its ends adapted to be engaged by said movable main leaf and also having an abutment adjacent one of its ends for engagement with said stationary main leaf to limit the pivotal action of the hinge.

6. A hinge comprising a stationary main leaf, a movable main leaf pivoted to said stationary main leaf, a pivotal auxiliary leaf 70 adapted to engage said stationary main leaf and support said movable main leaf in one position, said auxiliary leaf being adapted to be moved by said movable main leaf into engagement with said stationary main leaf 75 to support the movable main leaf in a second position.

In testimony that I claim the foregoing I hereunto affix my signature.

ROCKWELL M. MILLIGAN.
